UNITED STATES PATENT OFFICE.

ROBERT D. RADCLIFFE, OF NEW ROCHELLE, NEW YORK.

REPAIR-TOOL.

1,185,241.

Specification of Letters Patent. Patented May 30, 1916.

Application filed December 7, 1911. Serial No. 664,503.

To all whom it may concern:

Be it known that I, ROBERT D. RADCLIFFE, a citizen of the United States, and resident of New Rochelle, in the county of Westchester and State of New York, have invented certain new and useful Improvements in Repair-Tools, of which the following is a specification.

The present invention relates to repair tools intended for use in removing valves from motors.

It is well known that the valves of internal combustion engines are usually maintained normally closed by means of springs, bearing against rigid portions of the motor frame or valve casing and against cups, or similar elements, secured to the valve stems in proper position. When it is desired to remove the valves, it is necessary to release the same from the pressure of the springs applied thereto. Various devices have been proposed heretofore for this purpose, comprising usually a plurality of levers for compressing the valve spring. These devices are, however, too complicated and, on the other hand, necessitate the removing of the spring from the valve stem. When, therefore, the spring is, after the repairing operation, again to be applied to the stem, much time is wasted and great trouble experienced.

The main object of the present invention is to provide a simple and efficient tool which will, in removing the valve, hold the spring compressed in proper position relative to the valve casing, so that the valve stem and the valve thereon can be easily and conveniently applied to the motor after the grinding operation.

With these and other objects in view, which will more fully appear as the nature of the invention is better understood, the same consists in the combination, arrangement and construction of parts hereinafter fully described, pointed out in the appended claim and illustrated in the accompanying drawings, it being understood that within the scope of the claim many changes may be made in the size and proportion of the several parts and minor details of construction without departing from the spirit or sacrificing any of the advantages of the invention.

One of the many possible embodiments of the invention is illustrated in the accompanying drawings, in which:

Figure 1 is a vertical sectional view through the valve chamber and adjacent parts of a motor, showing the tool forming the subject matter of this invention applied thereto; Fig. 2 is a similar view showing the parts in other positions; Fig. 3 is a plan view, partly in section, of a detail of construction; Fig. 4 is a front elevation of the tool; Fig. 5 is a side elevation thereof; Fig. 6 is a plan view of the same; Fig. 7 is a section taken on line 7—7 of Fig. 4; and Fig. 8 is a plan view of the blank of which the tool is formed.

In the drawings, the numeral 10 indicates the valve casing of an internal combustion engine, having a valve seat 11 for the valve 12, of the puppet type, which is attached to a stem 13. The stem passes through the usual guide 14, and carries upon its lower end a cup 15, which is held in position upon the stem by means of a locking washer 16, engaging an annular recess 17 in the stem 13. A spring 18 bears against a shoulder 19 upon the guide 14 and against the cup 15. The locking washer 16 is normally located within a recess 15' in the cup 15, thereby being prevented from disengaging itself from the stem 13.

The cam shaft of the engine is denoted by the numeral 20, and the cam by the numeral 21. This cam engages the stem operating pin 22, guided in its movement by an extension 22' of the motor frame, and kept by means of the spring 18 in engagement with the stem 13.

The operation and function of the parts described so far is well known, and these parts have been described only to illustrate the manner of using the improved tool.

The repair tool is made, for instance, of sheet metal, preferably by stamping operations. The blank consists of a quadrangular body portion 23, having upon two parallel sides thereof extensions 24, 24. This blank is bent to form a substantially tubular member in such a manner that the projections 24, 24 are arranged at a distance from each other which is greater than the diameter of the locking washer 16. The body portion of the blank, when bent to its proper form, ex-

tends through an angular distance which is considerably greater than 180° , as clearly shown in Fig. 7 of the drawings. The diameter of the tool must, of course, be larger than the diameter of the guide 22' of the stem operating pin 22.

While herein the tool has been described as being made of sheet metal, it is obvious that it may be cast just as well, or it may be made of any other suitable rigid material.

The operation of this tool is as follows: When the valve with its stem are to be removed from the motor for the purpose of 15 regrinding said valve and seat, the cam 21 is brought into the position shown in Fig. 1 of the drawings, whereby the valve 12 will be fully lifted from its seat. The spring 18 is thereby compressed. The 20 height of the tool corresponds to the distance between the lowermost plane of the cup 15 and the uppermost plane of that portion of the engine frame through which the operating stem protrudes. The tool can 25 thereby easily be placed in concentric relation to the valve operating pin 22 to support the cup 15. When now the cam shaft is turned to allow the valve 12 to occupy the valve seat, the repair tool will hold the 30 spring in its compressed position, as clearly shown in Fig. 2 of the drawings, and permit thereby the withdrawal of the locking washer 16 from the annular recess 17 in the valve stem 13. The valve stem is thereby 35 released, and can be easily disengaged from its guide 14 for repair purposes. It will be observed that the repair tool keeps, even after the valve and its stem have been removed from the engine, the cup 15 in concentric relation to the longitudinal axis of 40 the stem operating pin 22, and holds the spring 18 compressed. When the seat and the valve have been reground, the valve is placed in position upon the valve casing, 45 the locking washer 16 seated in the recess 17 of the stem, the cam shaft rotated in order to lift the valve from its seat, after which the tool is withdrawn, leaving thereby

the parts of the engine in their normal operative positions relative to each other.

It will be observed that, since the projections 24 of the tool are brought as close together as the construction of the valve stem and its operating parts will permit, the cup 15 will be properly supported in a substantially horizontal plane, and, since the body portion of the tubular tool extends over an angular distance which is considerably greater than 180° , the repair tool will be held in a vertical position, in other words 55 it will not be tilted over by the pressure of the spring 18 exerted thereon. The result of this will be that the spring will be maintained compressed, permitting thereby the valve stem to be conveniently placed in position upon the valve casing after the repairs have been finished. It will be noted that the pipes or other obstructions on or adjacent the valve stem do not prevent the insertion of the repair tool, the latter being 60 of small dimensions only, in fact smaller in diameter than the cup 15.

While herein the device has been described in use upon a particular type of valve operating mechanism, it is obvious 75 that the same can be made use of upon almost every type of internal combustion engines, the only thing to be changed being the height of the tool and the distance between the extensions 24, 24 thereof. This 80 distance might be very small, if the cup 15 is held upon the stem 13 by means of a cotter pin.

What I claim is:—

A repair tool of the character described 85 comprising a tubular body entirely open at its ends and having a slot running the length thereof, said slot being narrowed at one end.

Signed at New York, in the county of 90 New York and State of New York, this 19th day of October, A. D. 1911.

ROBERT D. RADCLIFFE.
